UNITED STATES PATENT OFFICE.

GUSTAV HUBER, OF STUTTGART, GERMANY.

PRODUCTION OF OVERSEAMS.

Application filed February 19, 1926, Serial No. 89,278, and in Germany November 30, 1925.

My invention relates to the production of an overseam such as described in my application, Ser. No. 547093, filed on March 27, 1922, and the object of my present invention is to further improve the overseam. This I accomplish firstly in that I cause the overseam needle to stitch not only through the bent edges on both sides of the seam uniting two pieces of fabric, but to stitch also through the rib produced by said seam, and secondly in that, instead of one looper cooperating with the overseam needle, I use two loopers, each carrying a thread, which threads meet in the center over the regular seam, where they are tied. In this manner, I produce an overseam which is more durable than the overseam described in my above said application and at the same time has a very attractive appearance.

For a full understanding of my invention, I refer to the appended drawing, in which I have illustrated the same and in which Fig. 1 is a side elevation showing the sewing together of two pieces of fabric, the trimming of the sewed together edges and the production of the overseam; Fig. 2 shows the finished seam and overseam, as seen from the inside of the united pieces of fabric; Fig. 3 shows the outside of the two sewed together and overseamed pieces of fabric, the overseam being shown in section on the left-hand side of the figure; Fig. 4 is a cross-sectional view showing the production of the overseam by the overseam needle, and the two cooperating loopers; Fig. 5 is a perspective view of Fig. 1 showing the movable end of the curved arm containing the feed-mechanism for the overseam-needle.

In the drawing, the two pieces of fabric to be sewed together and overseamed are indicated at *a* and *b*. As they are fed toward the movable end *u* of the curved arm (not shown) they pass one above and the other below the loosely mounted pointed member *c* of said arm (Fig. 5) under the presser-foot *d* toward the sewing needle *e* which sews the two pieces of fabric *a* and *b* together along their edges. The projecting portions *v* of the united edges are then trimmed off by the upper and lower coacting knives *w* and *x* of the trimming device provided in close proximity to the needle *e* as clearly shown in Fig. 5, the mounted edges forming a rib *f* more clearly shown in Fig. 4. In this movable portion *u* of the curved arm is located the feeder *g* for the overseam

needle *k*. Said feeder engaging the rib presses the same, as best shown in Fig. 4, into a recess *h* provided in the rounded arm *i* adapted to cooperate with the feeder *g*. In this position of the rib *f*; the overseam needle *k* stitches not merely through the bent edges of the two pieces of fabric *a* and *b* on both sides of the rib *f* but stitches also through this rib itself, as clearly shown in Fig. 4. Above and below the feeder *g* are provided the curved arm abutments *s* and *t* whereby the stitching lines for the overseam needle as indicated at *l* and *m* in Figs. 2 and 3 are determined, which stitching lines, according to the position of the abutments *s* and *t* may be varied.

At *n* in Figs. 1, 4 and 5 is shown the one and at *p* the other looper cooperating with the overseam-needle *k*. In the position of the parts shown in Fig. 4, the looper *n* has completed its forward movement having passed through the loop *o* of the thread carried by the overseam needle *k*. While the looper *n* is at rest in this position, the looper *p* passes between the looper *n* and its overseam thread *r* carrying its own thread *q* to the overseam needle *k* as the same is starting on its descent. The direction of this looper movement is shown by the arrow 1 in Fig. 4. As the looper *p* oscillates back, it withdraws from the loop of the overseam thread *r*, so that thread *r* comes to rest on thread *q* and by a proper regulation or equalization of the thread tensions, the two threads *q* and *r* are tied in the center between the two stitching lines *l* and *m*, as clearly shown in Figs. 1, 2 and 5.

At *y* in Fig. 1 is shown the looper cooperating with the sewing needle *e*, which passes through the stitch-hole shown at *z* in Fig. 5. The length of stitch of the overseam is greater than the length of stitch of the seam, such length being preferably about twice the seam stitch length.

I claim as my invention:

1. A seam for joining abutting edges of two pieces of fabric consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, and means locking said thread loops.

2. A seam for joining abutting edges of two pieces of fabric consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, and means locking said thread loops, said means comprising an over-edge thread.
3. A seam for joining abutting edges of two pieces of fabric consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, and means locking said thread loops, said means comprising two over-edge threads interlocking above said abutting edges.
4. In combination with a primary seam joining the abutting edges of two pieces of fabric, a secondary seam consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, and means locking said thread loops, said means comprising an over-edge thread.
5. In combination with a primary seam joining the abutting edges of two pieces of fabric, a secondary seam consisting of a series of thread loops, each thread loop entering and emerging from the same face of one of the pieces of fabric at one side of the abutting edges, and then passing through both pieces of fabric and joining the same at their abutting edges, and then entering and emerging from the same face of the other piece of fabric at the other side of the abutting edges, and means locking said thread loops, said means comprising an over-edge thread.
6. In combination with a primary seam joining the abutting edges of two pieces of fabric, a secondary seam consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, and means locking said thread loops, said means comprising two over-edge threads interlocking above said abutting edges, and means locking said thread loops, said means comprising two over-edge threads interlocking above said abutting edges.
7. In combination with a primary seam joining the abutting edges of two pieces of fabric, a secondary seam consisting of a series of thread loops, each thread loop entering and emerging from the same face of one of the pieces of fabric at one side of the abutting edges, then passing through both pieces of fabric and joining the same at their abutting edges, and then entering and emerging from the same face of the other piece of fabric at the other side of the abutting edges, the stitches of said secondary seam being of greater length than the stitches of said primary seam, and means locking said thread loops.
8. In combination with a primary seam joining the abutting edges of two pieces of fabric, a secondary seam consisting of a series of thread loops, each thread loop entering and emerging from the same face of one of the pieces of fabric at one side of the abutting edges, and entering and emerging from the same face of the other piece of fabric at the other side of the abutting edges, the stitches of said secondary seam being of greater length than the stitches of said primary seam, and means locking the said thread loops, comprising two over-edge threads interlocking above said abutting edges.
9. The process of joining two pieces of fabric having abutting edges comprising passing thread loops into and out of the same face of one piece of fabric, then through the two edges, then into and out of the same face of the other piece of fabric, and locking the loops.
10. The process of joining two pieces of fabric comprising forming a primary seam through their abutting edges, then forming a secondary seam covering said primary seam by passing thread loops into and out of the same face of one piece of fabric, then through the two abutting edges, then into and out of the same face of the other piece of fabric and locking the loops.
11. The process of joining two pieces of fabric comprising forming a primary seam through their abutting edges, then forming a secondary seam covering said primary seam, the length of whose stitches is greater than the length of the primary seam stitches.
12. The process of joining two pieces of fabric comprising forming a primary seam through their abutting edges, then forming a secondary seam covering said primary seam by passing thread loops into and out of the same face of one piece of fabric, then through the two abutting edges, then into and out of the same face of the other piece of fabric, the length of the secondary seam

stitches being greater than the length of the primary stitches, and locking the loops.

13. The method of producing a combined seam and overseam in one operation which 5 consists in first uniting the edges of two pieces of fabric by a seam, then spreading the united pieces of fabric and forming bent

edges thereof on both sides of the seam, and finally stitching through said bent over edges and said united edges with a thread 10 covering the first seam.

In testimony whereof I affix my signature.

GUSTAV HUBER.
